UNITED STATES PATENT OFFICE.

BERT B. MILNER, OF NEW YORK, N. Y.

CORRUGATED METAL PLATE.

1,425,207.

Specification of Letters Patent. Patented Aug. 8, 1922.

Application filed April 29, 1919. Serial No. 293,462.

To all whom it may concern:

Be it known that I, BERT B. MILNER, a citizen of the United States, residing at New York, in the county of New York and 5 State of New York, have invented certain new and useful Improvements in Corrugated Metal Plates, of which the following is a specification.

My invention relates to the manufacture 10 by pressing of metal plates or other metal articles formed with corrugations, ribs, embossments, channels or other configurations necessitating the stretching or thinning of the metal during the pressing operation. 15 The primary object of the invention is to compensate for the unequal stretching or thinning of the metal at different places under conditions imposed by the pressing operation by making the original plate or 20 blank thicker in the regions where the stretching or thinning is greatest. The invention is applicable to the manufacture of metal articles of various different sorts but for purpose of illustration will be shown 25 and described in connection with the manufacture of corrugated plates suitable for use as end wall plates of railway cars.

In the drawings—

Figure 1 shows the application to a rail- 30 way car of a corrugated plate manufactured in accordance with my invention, this figure being a broken perspective view of the end of a railway car employing a corrugated end sheet manufactured in accordance with 35 my invention.

Fig. 2 is a plan view of the plate before it is corrugated.

Fig. 3 is an end view of the plate to show the variation in thickness which, for pur- 40 poses of illustration, has been exaggerated.

Fig. 4 is a somewhat diagrammatic view of the face of the finished plate.

Fig. 5 is a sectional view on line 5—5 of Fig. 4.

45 Figs. 6 to 10 inclusive are diagrams which may be located on Figs. 2 and 4 as follows: Fig. 6 on line 6—6 of Figs. 2 and 4; Fig. 7, on line 7—7 of Fig. 4; Fig. 8, on line 8—8 of Fig. 2; Fig. 9, on line 9—9 of Fig. 50 4, and Fig. 10, on line 10—10 of Fig. 2.

55 Figs. 11 to 14 inclusive, are diagrammatic views illustrating a modified form of plate and method of manufacture; Fig. 11 being an edge view of the plate, before corrugat- 105 ing, along the edge parallel to the lines of the intended corrugations; Fig. 12, a view

of the face of the plate, the dotted outline indicating the plate before corrugating, the full line the plate after it has been corrugated, and the dot and dash line the plate 60 after being trimmed to rectilinear shape; Fig. 13, being a section on line 13—13 of Fig. 12, and Fig. 14, a section on line 14—14 of Fig. 12.

Like characters of reference designate like 65 parts in the several figures of the drawings.

I shall first describe the plate and method of manufacturing the same illustrated in Figs. 1 to 10 inclusive. The finished plate 25 here shown is formed with a plurality 70 of substantially parallel corrugations 26 which, to all intents and purposes, merge one into the other so that the corrugated portion of the plate has a sinuous configura- 75 tion as shown in Fig. 1. In this figure the 75 finished plate forms the end sheet of a gondola car, the vertical edges of the plate being flanged over at 27 and attached to the side walls 28 of the car. The upper edge of the sheet is provided with an angular top 80 chord 29. The portion 30 of the uncorrugated plate 31 (Figs. 2 and 3) is thicker than the rest of the plate. This thickness is indicated by the letter 'c'. The marginal 85 portions 32 of the plate are the thinnest 85 portions, the thickness being indicated by 'a'. The portions 33 adjacent the marginal portions increase in thickness from the thickness 'a' of the margins to a thickness indicated by 'b'. The portions 34, 34 of the plate 90 intervening between those designated 33 and 30 have a thickness which varies from 'b' to 'c'.

A plate so formed, by rolling, for example, through rolls of suitable contour, is heated 95 to red heat and pressed between dies having a configuration proper to form in said plate corrugations of the character indicated in Figs. 4, 5, 7 and 9, that is to say, each corrugation will have terminal portions 33', 100 a center portion 30', the contour of which is shown in Fig. 9, and intervening portion 34, the contour of which will vary from that shown in Fig. 7 to that shown in Fig. 9. Where a finished plate is desired which will 105 be of substantially uniform thickness on all places the thickness of the blank before being corrugated along any given line trans- 110 verse to the intended corrugations is to be proportionate, in accordance with my in- vention, to the amount of stretch of the metal along such line when the plate is sub-

jected to pressure in the operation forming the corrugations. When the plate is rolled or otherwise formed to give it the varying thicknesses above indicated, the operation 5 of developing the corrugations will thin the plate at the thicker portions so as to reduce it to substantially the same thickness throughout, namely, to the thickness of the marginal portions 32. Assuming that during 10 the pressing operation the edges of the plate are restrained so that they will not draw in, the thickness of the plate along different transverse lines is to be determined with reference to the corrugation contours, 15 as follows: Let A represent the distance between corrugation center lines and a , as above stated, the thickness of the marginal portions of the plate or of the finished plate at any point. Let B represent the length of 20 the contour line of a corrugation from center line to center line, on line 7-7 of Fig. 4, that is, along the line between portions 33' and 34' of any corrugation, b being the thickness of the original plate along this 25 same line. Let C represent the length of the contour line of the corrugation, between center lines, on line 9-9 of Fig. 4, that is, through the portion of the corrugation designated 30'; c being the thickness of the 30 original plate on a corresponding line. The original plate should be so proportioned that A will be to a as B is to b and C to c . Working this out for a corrugated plate a quarter of an inch thick, a standard thickness for 35 railway car ends, a will be one quarter of an inch, b .30725 and c .38025 or approximately so. This will give a corrugation, the middle portion of which will have a cross sectional configuration such as shown in 40 Fig. 9, as against a cross sectional configuration adjacent the pointed terminals represented by Fig. 7. In corrugating a railway car end sheet intended to extend across the car from side to side and formed from a 45 plate a quarter of an inch thick, it is difficult to press the corrugations more than approximately two inches deep with center lines six inches apart. Fig. 7 represents this depth of corrugation. By making the sheet 50 thicker at the middle it is possible to obtain a corrugation having a depth at the middle of the car indicated by Fig. 9 without making the center of the plate any thinner than the other portions. The additional depth 55 of the corrugations at the middle of the car gives the end increased strength and rigidity inasmuch as the corrugations function as beams, particularly where one merges into the other so that one corrugation cannot deflect without producing some deflection in the adjacent corrugations.

The above proportional dimensions are based upon the assumption that the plate, when being pressed, will not draw in at the 60 edges. If the plate does draw in to any ap-

preciable extent, it will be necessary, in order to get uniform thickness in the finished sheet, to take this factor into account in determining the thickness of the original plate along different transverse lines. This 70 solution will be apparent from the following description of the modified method illustrated in Figs. 11 to 14 of the drawings hereof.

According to this method, a sheet is provided in which the corrugations are of uniform cross sectional area throughout their length (except at their terminals), the expedient of making the original plate thicker at certain places than at others being, in this case, to compensate for the difference in stretch due to the inversely proportioned draw in of the edges, this method 75 contemplating a pressing operation in which the edges of the plate are free to draw 80 in when the plate is acted upon by the dies. Referring to Fig. 12, the dotted outline 35 indicates the outline of the original plate. The full lines 36, 37 form the outline of the plate after the corrugations have been 85 pressed into the same. The dash and dot line 38 indicates the finished plate after having been sheared to rectangular shape. As shown by lines 36, the edges of the plate 90 parallel to the corrugations will pull in the 95 most at the middle. The stretch of the metal will necessarily have to be greatest along the lines D, D intersecting the corrugations at the places where they start to taper, because while the pull in of the metal continues to 100 decrease from these lines outwardly to the ends of the sheet the transverse contour lines of the corrugations also diminish because of the tapering of the corrugations. The original plate is made thickest along 105 the lines D, D, as indicated at 39, Fig. 11. The thickness of the plate along the lines D, D, and the slope of the surfaces 40, 41 on opposite sides of these lines, will be proportioned to the stretch of the metal at these 110 places. This can be determined empirically. As a result of giving the plate this configuration, which can be accomplished in rolling, the finished corrugated sheet can be 115 made of substantially uniform thickness throughout, where this is desirable, whereas under present practice there has always been a tendency to thin the metal along the lines of the junction between the main portions of the corrugations and their 120 pointed terminals.

I do not claim herein the method of pressing above described as this method forms the subject matter of a co-pending application filed as a division hereof September 5, 1919, 125 Serial No. 321,915.

I claim:

1. As a new article of manufacture, a metal plate having pressed therein adjacently arranged relatively deep, narrow cor- 130

rugations terminating within the edges of the plates, which plate is of substantially uniform thickness throughout the corrugated portion thereof.

- 5 2. As a new article of manufacture, a metal plate having pressed therein relatively deep, narrow corrugations terminating within the edges of the plate, leaving flat uncorrugated marginal portions, and having 55
- 10 their maximum cross sectional area at the middle and tapering toward their extremities, which plate is of substantially the same thickness throughout the corrugated portion thereof.
- 15 3. A car end structure comprising a metal end sheet extending across the end of the car and anchored to the body thereof formed with a plurality of adjacently arranged corrugations which terminate within the edges 60
- 20 of the plate, leaving flat marginal portions, said plate being of substantially the same thickness throughout the corrugated and marginal portions thereof.
4. A car end structure comprising a metal end sheet extending across the end of the car and anchored to the body thereof, formed with a plurality of adjacently arranged corrugations pressed in one direction only from the plane of the sheet terminating 65
- 30 within the edges of the sheet, having their maximum cross sectional area at the middle, and tapering toward the extremities, said sheet being of substantially the same thickness throughout the corrugated portion 70
- 35 thereof.
5. A sheet metal article formed with adjacent embossments pressed in one direction only from the plane of the sheet and being of substantially uniform thickness throughout 75
- 40 out.
6. The combination with the body of a railway car, of an end structure comprising a plate provided with means for attaching opposite edges to the car body, the plate being formed with flat marginal portions and with pressed rigidifying embossments of 80
- 45 substantially equal thickness throughout the portion thereof midway between the aforesaid attached edges containing a greater aggregate volume of metal than the portions on opposite sides of said middle portion.
- 50 7. The combination with the body of a railway car, of an end structure comprising 85
- a plate provided with means for attaching opposite edges to the car body, the plate being formed with flat marginal portions and with pressed, rigidifying embossments of substantially uniform thickness throughout and the middle portions of the recesses formed by said embossments being of greater cross sectional area than the end portions thereof.
8. The combination with the body of a railway car, of an end structure comprising a plate provided with means for attaching opposite edges to the car body, the plate being formed with adjacently arranged pressed, rigidifying embossments which are parallel, project from one side of the plate only merge into each other and are of substantially uniform thickness throughout the middle portions of said embossments being deeper than the end portions thereof.
9. The combination with the body of a railway car, of an end structure comprising a plate provided with means for attaching opposite edges to the car body, the plate being formed with pressed, relatively deep and narrow rigidifying embossments substantially transverse to said attached edges, parallel and merging into each other and of substantially uniform thickness throughout the middle portions of said embossments being deeper than the end portions thereof.
10. The combination with the side walls of a railway car, of an end structure comprising a plate provided with means for attaching opposite edges thereof to said side walls, the plate being formed with adjacent pressed, horizontally disposed embossments of substantially uniform thickness throughout, which project from one side of the plate only, the middle portions of which are deeper than the end portions.
11. The combination with the side walls of a railway car, of an end structure comprising a plate provided with means for attaching opposite edges thereof to said side walls, the plate being formed with pressed, relatively deep horizontally and contiguously disposed embossments of substantially uniform thickness throughout, the recesses formed by said embossments being of greater cross sectional area at their middle portions than at their ends.

BERT B. MILNER.
